UNITED STATES PATENT OFFICE.

LUDWIG T. STRUCK, OF WASHINGTON, DISTRICT OF COLUMBIA.

TROUSERS.

1,128,824.

Specification of Letters Patent. Patented Feb. 16, 1915.

Application filed July 15, 1914. Serial No. 351,144.

To all whom it may concern:

Be it known that I, LUDWIG T. STRUCK, a citizen of the United States of America, residing at Washington, District of Columbia, have invented certain new and useful 5 Improvements in Trouzers, of which the following is a specification.

The invention relates to an improvement in trousers, and particularly to trousers constructed with a front flap or fall, and designed more particularly for use for firemen, letter-carriers, policemen, and others, where quick adjustment and complete accommodation is required with avoidance of 15 exposure.

The main object of the present invention is the provision in trousers of this type of means whereby the waist portion may be adjusted to suit the particular wearer and remain in such adjusted position about the 20 waist independent of the fall section.

A further object of the invention is the provision of means for adjusting the waist portion of the trousers to simulate the usual 25 belt connection, whereby when the trousers are being worn, they will have the appearance of the ordinary trousers supported by a belt.

The invention in the preferred form of 30 details will be described in the following specification, reference being had particularly to the accompanying drawings, in which:—

Figure 1 is a broken perspective of the improved trousers, the view being taken from one side. Fig. 2 is a similar view taken from the rear of the trousers. Fig. 3 is a front perspective, the fall portion being turned down. Fig. 4 is a broken perspective illustrating the belt connection. Fig. 5 is a broken perspective of the removable belt section. Fig. 6 is an enlarged perspective of the supporting hook.

In the accompanying drawing 1 designates the trousers. The forward portion of the trousers is formed to provide a flap or fall 2, usual in this type of garment, and preferably extending from one side seam to the other. The body of the trousers terminates 45 at the side seams beneath the fall portion, except for the band 3, which extends inwardly beyond the side seams, as shown. One terminal of the band has fixedly secured thereto an elastic strip 4 passed 50 through an eye member 5 and longitudinally adjustable by a buckle 6, the opposing ter-

50 minal of the band 3 being provided with a hook 7 to receive the eye 5. By this arrangement, the band 3 when properly arranged about the waist of the wearer by adjustment 60 of the connector 4 will act to properly support the trousers, independently of the position of the fall.

The front pockets 8 of the trousers underlie the fall portion, extending inwardly 65 from the side seams, as shown, the pocket openings being accessible beneath the edges of the fall portion when the latter is in raised or closed position.

The fall portion is provided on the inner 70 surface of its band and about centrally of its width with a hook 9, of substantial length with the bill 10 designed to engage over the connector 4 when the fall is elevated, thereby centrally connecting the fall 75 at a proper height, as clearly shown in Fig. 2. The fall portion is provided on its outer surface, at the upper edge, with a belt section 11, permanently secured to the fall, but arranged to simulate the usual removable belt. The band of the fall underlying 80 the terminals of the permanent belt 11 is provided with hooks 12, as clearly shown in Fig. 3.

The main waist length of the trousers 85 is provided with the usual belt loops 13 to receive a removable belt section 14, which belt section is approximately of a length to reach from one side seam of the trousers to the other across the rear. One terminal 90 of the removable belt section is provided on its inner surface with a hook 15, and the meeting ends of the fixed belt terminal 11 provided with an eye 16' to receive the hook. The remaining terminal of the removable 95 belt section 14 is provided with spaced hooks 16 on the inner side, a series of eyes 17 being also provided adjacent to and in longitudinal alignment with the hook. The trouser band 3 is also provided adjacent 100 each side seam with a series of eyes, 18 and 19, the eyes being arranged about centrally of the height of the band and in alignment longitudinally thereof.

In the use of the trousers, having ad- 105 justed the waist band as previously described through the use of the connector 4, it is ob- 110 vious that the trousers will remain sup- 115 ported by such band until opened by discon-necting the eye 5 from the hook 7. When it is desired to secure the fall in raised or closed position, it is turned upwardly and

the bill 10 of the hook 9 passes over the connector 4. The hooks 16 of the removable belt portion 14 are engaged in the appropriate holes 18, and the hook 12 of the permanent belt 11 engaged in the appropriate hole 19. The hook 15 of the removable belt section is then engaged with the eye 16' of the permanent belt section 11, and the hook 12 at the opposite end of the permanent belt section engaged in the appropriate opening 17. The belt is thus adjusted about the waist in a manner to simulate a belt connection and the fall may be freed in a simple, obvious manner without disturbing other than the connections between the permanent belt section and the removable belt section.

What is claimed is:—

1. A trousers having a fall portion, the band of the trousers being divided beneath the fall portion, an adjustable elastic connector joining the terminals of the band, a hook carried by the fall portion to engage said connector, a permanent belt secured to the fall portion, a removable belt overlying the trousers band, and adjustable connections between said removable belt and the trousers band, and between said removable and permanent belts.

2. A trousers having a fall portion, a belt 30 permanently secured thereto and terminally formed with connectors, the band of the trousers being formed beyond the fall portion with eyes, and a removable belt co-operating with said band and having connectors to coöperate with said eyes and with the connectors of the permanent belt.

3. A trousers having a fall portion, a permanent belt carried thereby and formed with a terminal eye, end connectors carried 40 by the fall portion, the band of the trousers being formed with eyes to receive one of said connectors, a removable belt portion formed with a terminal connector to co-operate with the eye of the permanent belt, 45 said removable belt being provided with eyes and with spaced connectors, said eyes being adapted to coöperate with the connectors of the fall portion, the band of the trousers being formed with spaced eyes to 50 coöperate with the spaced connectors of the removable belt portion.

In testimony whereof I affix my signature in presence of two witnesses.

LUDWIG T. STRUCK.
